UNITED STATES PATENT OFFICE.

LEON E. LA BOMBARD AND MELVIN H. SIDEBOOTHAM, OF CHELSEA, MASSACHUSETTS,
ASSIGNORS TO SPECIALTY AUTOMATIC MACHINE COMPANY, OF CHELSEA, MASSA-
CHUSETTS, A CORPORATION OF MASSACHUSETTS.

TIMED FEEDER.

Application filed June 24, 1922. Serial No. 570,697.

To all whom it may concern:

Be it known that we, LEON E. LA BOMBARD and MELVIN H. SIDEBOOTHAM, citizens of the United States, and residents of Chelsea, in the county of Suffolk and State of Massachusetts, have invented certain new and useful Improvements in Timed Feeders, of which the following is a specification.

This invention relates to mechanism for detaching blanks or sheets from the bottom of a pile, and advancing them singly toward other mechanism for further treatment, such mechanisms being known as bottom feeders, and the invention has particular reference to mechanism for detaching and advancing the blanks in spaced relationship. Devices or mechanisms of this type are commonly known as timed feeders because they are usually employed for feeding the blanks to secondary mechanism which operates on predetermined longitudinal portions or areas of the blanks and which, therefore, renders it necessary that each blank shall reach said secondary or treating mechanism at a certain time in the operation thereof.

Feeders which successively push blanks from the bottom of a pile have a tendency to start more than one blank forward. To overcome this tendency is one of the objects of our invention. In attaining this object we provide for slightly lifting the pile of blanks while the bottom blank is being pushed forward to be engaged by forwarding mechanism, thereby effecting the primary result of eliminating or reducing friction between the under surface of the bottom blank and whatever stationary supports are employed for the pile, and the secondary result of reducing liability of a second blank starting, with the bottom blank, into the throat or passageway through which the blanks must pass singly from the hopper.

Another object of the present invention is to provide a bottom feeder capable of successively operating on blanks which are not of uniform thickness, or which have something else attached thereto such as the tape handles attached to the blanks for making ice-cream pails.

Another object is to provide improved throat mechanism for alternately opening and closing the passageway for the blanks leaving the feeder.

With the above and other objects in view,

the invention consists in the construction and combination of parts substantially as hereinafter described and claimed.

Of the accompanying drawings:

Figure 1 is a perspective view of one of our improved feeders in one of its embodiments.

Figure 2 represents a longitudinal section of the same.

Figure 3 is a detail plan view of one of the lifting and feeding disks with an adjustable peripheral mounting or hump.

Figure 4 is a view similar to a portion of Figure 2 but showing a modified and sometimes preferred form of the front rotary member at the exit throat.

While the feeder herein described and claimed is capable of use in connection with various kinds or types of machines for treating the blank fed, such as the making of envelopes or the printing of sheets, it has been designed especially for use in connection with machines for making egg boxes such as illustrated in our application Serial No. 442,868, filed Feb. 5, 1921.

In the drawings, portions of the frame are indicated at 12, the side portions being connected by a slotted cross bar 13 and one or more tie rods. Mounted on a rod 14 and adjustable longitudinally thereof are two brackets 15 each having an upright wall 75 plate 16 secured thereto.

Extending along and secured to the lower edge of each wall plate is a bar 17 the other ends of the two bars being supported by a fixed cross bar 14* (Fig. 2). The upper 90 surfaces of the bars 17 provide ledges for the marginal portions of the lower blank of a pile. One blank is indicated by dotted lines in Figure 1.

When the blanks to be fed are quite wide, 95 and the side walls 16 of the hopper are set quite far apart it is desirable to employ intermediate supports other than the rotary disks hereinafter described. To this end we provide blocks 18 removably and adjustably clamped on the rod 14, said blocks having strips 19 extending parallel with the bars 17 and level with the ledge surfaces thereof.

For the reasons explained hereinafter we 105 prefer, for some purposes, that the ledges 17 and floor strips 19 shall not be smooth but shall be super-frictional. They may have rubber surfaces or may be roughened in any

suitable manner as indicated in Figure 1. Either rubber or roughening provides extra or super-frictional resistance to any movement of blanks resting thereon.

- 5 When the blanks to be fed have irregular edges so that the side plates 16 can not be relied upon to hold the pile properly, we employ vertical side guiding strips 20 supported by studs 21 having shanks 22 extending through the slot of the bar 13 (Fig. 2) and secured in proper laterally adjusted positions by nuts 23. The lower ends of the vertical guides do not extend quite to the level of the strips 19 and ledges 17 but terminate at a point (see Fig. 2) to permit laterally projecting portions of the lower or bottom blanks to successively pass them.
- 20 Mounted in bearings on the frame are three shafts 24, 29, 35 which are driven continuously and synchronously by power and through gearing not necessary to illustrate. Secured to the shaft 24 is a rotary member which may be a wheel 25 as in Figures 1 and 2 or a segment 25* as in Figure 4. Said 25 rotary member has a friction peripheral surface or surfaces such as rubber plugs 26.

A roll 27 carried by shaft 28 is driven at the same peripheral speed (but in opposite directions) as that of the wheel 25 or 30 segment 25* to ensure the advance of the blank fed under the gate strip presently described.

35 Adjustably secured to the shaft 29 are the hubs 30 of two disks 31. Each disk has a portion of its periphery raised. In other words each disk is cam-shaped, its higher portion forming what is hereinafter referred to as a hump. Preferably but not necessarily it comprises two plate members 33 40 (Fig. 3) one of which is secured in fixed position on the periphery of the disk and has a recess to receive a tongue portion of the other member which is slotted and has a set screw 32 passing through it into the 45 disk.

50 By loosening the set screw 32, shifting the longitudinal position of the member 33 which has the tongue portion, and then tightening said screw, the effective length of the hump may be varied when conditions hereinafter explained require it. Figures 2 and 4 do not illustrate this feature because we do not limit ourselves to machines which include it.

55 Surrounding and tightly fitting each disk 31 is a band 34 of rubber or other suitable material to frictionally engage the lower or bottom blank of a pile in the hopper and effect edgewise movement of said blank.

60 Secured to the shaft 35 is the hub 36 of a third disk 37 having a peripheral hump plate or support 39 and a surrounding friction band 40. The said disk 37 is in line with the space between the two disks 31, and 65 all three are practically alike in structure.

As best illustrated by Figure 2 the three cam shaped disks with their higher portions forming humps are of such size and are so mounted and driven that, when revolving in the direction of the arrows, only those portions of the friction bands which extend over the humps will touch the bottom blank of a pile. This is because the normal support for the pile comprises the ledges 17 and (when used) the strips 19 which are at a height above the axes of the shafts 29, 35, less than the radius which includes the humps and greater than the radius not including the humps. In other words, the pile is alternately lifted and lowered relatively to the normal support for the pile and the bottom blank is urged forward during such lifting by the portions of the friction bands which extend over the humps. As these portions become worn, the bands 85 can be shifted far enough around on the disks to bring onto the humps other portions which are not worn because they have had no work to do.

Each blank acted upon by the humped friction feeders is pushed through a passageway which is alternately opened and closed at the proper times as we will now describe.

90 A vertical bar 41 having slots 42 through which screws 43 pass into the cross bar 13 constitutes an abutment for the front edges of the pile of blanks in the hopper. Its lower end is preferably convex as shown in Figure 2 and it is held in fixed position by the screws 43 with the tip of its lower end at such height above the path of the revolving friction studs 26 as to just permit the passage of a single blank. The slots and screws 42, 43, are to permit the bar 41 to be 95 adjusted to provide a wider or narrower passageway according to the thickness of the blanks or sheets to be fed.

95 Mounted to slide in a suitable vertical guideway of the bar 41 is a gate strip 44 the lower end of which, when said strip is not lifted, extends below the tip of the bar 41 to obstruct the passage of a blank. Secured to and rising from a lateral ear of the gate strip 44 is a pin 45 guided in a lug or 100 block 46 carried by the bar 41. A spring 47 coiled around the pin 45 and confined between the lug 46 and the ear of the gate strip acts lightly to tend to hold the gate strip in its lower, closing, position. Said 105 gate strip is lifted intermittently to open the passageway for a blank, by an arm 48 of a rock shaft 49, said arm 48 extending under the ear of the gate strip. A second arm 50 secured to the shaft 49 is acted upon by a cam disk 51 carried by a shaft 52, a spring 53 being connected to the arm 50 to hold the arm 50 in contact with the cam. The spring 53 is of sufficient strength to 110 overcome the resistance of the spring 47 and 115

effect lifting of the gate strip when the end of arm 50 is bearing on the low portion of the disk 51. When the cam lifts the outer end of arm 50, the arm 48 is lowered and the spring 47 slides the gate strip 44 down.

In operation, assuming that the lateral positions of the wall plates 16 and guide strips 20, have been adjusted to suit the shape and size of the blanks to be fed, and that the disks 31, 37, have been laterally and rotatively adjusted on their shafts to cause their friction humps to properly engage the bottom blank of a pile, the timing of the relative operation of the parts is such that just as the gate strip 44 rises the friction humps begin to act, lifting the pile so that the bottom blank is free from the extra or super-frictional retarding effect of the normal supports 17, 19. As the humps move forward they start the bottom blank through the gate or passageway and said blank is grasped and aided in its forward movement by the coaction of the driven roll 27 with the wheel 25 or segment 25%.

The lengths of the humps is considerably less than that of the blanks so that when the disk 37 and its hump 40 has rotated far enough to cease to act on the bottom blank or, in other words, when the rear edge 30 of the bottom blank has passed beyond the point where the said hump 40 acts upon it, the weight of the pile causes the rear portion of the next blank to settle down on the normal support 17, 19, the super-frictional engagement of which prevents a second blank from being dragged along by the one which is passing out under the gate strip. As soon as the rear edge of the moving blank passes beyond the point where the humps of the disks 31 act upon it, all feeding tendency ceases until the humps again reach about the positions shown in Figure 2.

The described adjustment of the humps as to length (Fig. 3) when the structure therefor is employed is to provide for properly acting on blanks of different length.

Since only portions of the friction bands 34, 40, are at sufficient distance from the axes of rotation of the shafts 30, 36, to effect any feeding, said portions constitute a friction feeder to act on successive lower blanks of a pile in the hopper. The rotation of the disks carrying these friction humps causes their operative height to be intermittently varied relatively to the height of the normal super-frictional support 17, 19, thereby reducing or eliminating retarding friction during feeding periods.

An important function of this structure is that it reduces liability of the second blank (the one next above the bottom blank) being forced into the outlet below the gate strip 44 by the friction of the bottom one which is being fed out. This is due to the fact that the humps are adjustable in length

to meet requirements. In Figure 2 the front and rear humps are indicated as of substantially the same length, but it will be readily understood that the humps 33 of the front shaft 29 may be increased in length and the hump 39 of the rear shaft 35 may be shortened either by shifting lengthwise the member having the tongue (Fig. 3) or by entirely removing that member. Then when the blanks being fed are of such length as to extend back over all of the humps, the rear edge of the bottom blank will pass forward beyond the rear hump 39 and result in permitting the rear portion of the next or second blank to be pressed down, by the weight of the pile above it, onto the super-frictional surface of the normal support 17, 19, whereby said second blank will be held back while the forward humps 33 are still exerting a feeding action on the bottom blank. This enables the maximum feeding action to be exerted on the lower blank and the maximum retarding action to be effected on the second blank, such action continuing successively on the blanks as each bottom one is entirely fed out.

The cam 51 is so formed and timed as to its operation that the gate strip 44 is free to descend before the rear edge of the fed blank passes out. In other words, the lower end of the gate strip bears on the surface of the rear portion of the outgoing blank and as soon as the rear edge passes out, the gate strip drops and does not rise until just as the humps begin to act on the next bottom blank. By this mechanism we ensure absolute uniformity of the spacing between successively fed blanks to enable each blank to reach position for treatment such as folding or printing without having another blank so close to it as to interfere with said treatment. For these reasons the mechanism is especially adapted for use in connection with machines which treat the blanks while briefly held in arrested positions, such as explained in our application hereinbefore referred to.

It is to be understood that Figure 3 illustrates a structure of adjustable hump plates suitable for all three of the disks 31, 37, although Figures 1, 2 and 4 do not illustrate the humps as adjustable. Instead of forming each by means of two members, we may provide single segmental plates of different lengths and substitute or interchange sizes to suit the blanks to be fed.

When the blanks to be operated upon are plain flat ones, without attachments, a feed wheel having a complete circular periphery such as shown at 25 in Figure 2 is usually preferable. With such a wheel however difficulty is experienced if the blanks have attachments (such as the tape handles of ice cream pail blanks) or if the blanks have (due to partial preliminary folding or

otherwise) doubled or extra-thick portions. Such tape or extra-thick portions are liable to catch upon the gate strip or choke the outlet throat. We have discovered that by 5 cutting away a part or parts of the wheel under the gate strip, so as to provide a recess capable of receiving such tape or extra-thick portions, blanks of the kind referred to can be accurately fed. In such case the 10 blanks are stacked in the hopper with single-thick edge portions against the abutment member 41, the tapes or extra-thick portions being at the rear. Then, by the time each blank has passed far enough to be under 15 the control of the usual forwarding mechanism of the machine to which the blanks are supplied by this feeder, its tape or extra thickness will be accommodated in the cut-away or recessed portion of the wheel so as 20 not to catch. In Figure 4 we have illustrated such a wheel as cut away to such an extent as to leave practically a segment 25^x. Obviously however the cutting away need not be so extensive. In effect the member 25^x is a wheel with a very extensive 25 recess.

As hereinbefore stated, feeders which successively push blanks from the bottom of a pile have a tendency to start more than 30 one blank forward. If two or more blanks so start, their front edges become wedged under the restricting abutment such as that illustrated at 41. To aid in overcoming this tendency we provide means for slightly 35 withdrawing the pile of blanks, or causing said pile to retreat, just as or immediately after the bottom blank is advanced. It is particularly desirable to do this when the blanks have tape or other attachments or 40 have extra-thick portions as hereinbefore described and when for this reason the feed wheel under the abutment is cut away or recessed. To illustrate this, assume that the segmental member 25^x (Fig. 4) has moved 45 far enough in the direction of the arrow to no longer afford any support for the front edge of the lower blank. Unless the blanks are very stiff, the front edges of two or more would be liable to drop down so that as said 50 member moves up toward the position shown in Figure 4 said edges would become wedged under the abutment 41. To effect the retreat or slight drawing back of the pile at the proper times, we provide the 55 following mechanism:—The rod 14 is supported by arms 55 of a rock shaft 54, the latter having another arm 56 actuated by a cam 57 on the shaft 35. The result of this structure is that as soon as the bottom 60 blank is advanced far enough to expose any portion of the under surface at the rear of the next blank, the friction supports 17, 19, act on that exposed portion to draw it back. 65 By the employment of the side guiding strips 20 we provide adjustable registering

devices for the blanks of a pile to hold them squared up, preventing any from becoming askew.

By the term "blanks" used herein we do not mean to limit ourselves to any particular shape or kind of material. The term is intended to apply as well to sheets of any kind to be fed to box-making machines, printing presses, or other machines which treat or operate upon them.

Having now described our invention, we claim:

1. A blank-feeding mechanism including a normal support for a pile of blanks, said support being surfaced to frictionally retard blanks, a friction feeder to act on successive lower blanks of the pile, and means for intermittently varying the relative height of said normal support and friction feeder to reduce the retarding effect of the normal support when the feeder acts on each lower blank.

2. A blank-feeding mechanism including a normal support for a pile of blanks, said support having a super-frictional retarding surface, a friction feeder to act on successive lower blanks of the pile, and means for intermittently varying the relative height of said normal support and friction feeder to reduce the retarding effect of the normal support when the feeder acts on each lower blank.

3. A blank-feeding mechanism including a normal support having an extra frictional surface for a pile of blanks, and a friction feeder to act on successive lower blanks of the pile, said feeder including forward and rear intermittently operating members timed to cause the rear member to cease operating and permit the rear portion of the second blank of the pile to engage said extra frictional surface while the forward member continues to feed the bottom blank.

4. A blank-feeding mechanism including a normal support having an extra frictional surface for a pile of blanks, and forward and rear rotary members having raised friction feeding surfaces timed in operation to cause the rear member to cease feeding and permit the rear portion of the second blank of the pile to engage said extra frictional surface while the forward member continues to feed the bottom blank.

5. A blank-feeding mechanism including a normal support having an extra frictional surface for a pile of blanks, a friction feeder to act on successive lower blanks of the pile, means for intermittently varying the relative height of said normal support and friction feeder to reduce the retarding effect of the normal support when the feeder acts on each lower blank, and an intermittently closed and opened gateway for the passage of the lower blanks.

6. A blank-feeding mechanism including

- a normal support having a super-frictional surface for a pile of blanks, and a friction feeder intermittently movable toward and from the lower blank of the pile.
- 5 7. A blank-feeding mechanism including a normal support having a super-frictional surface for a pile of blanks, a friction feeder intermittently movable toward and from the lower blank of the pile, a gate-controlled 10 passageway for successive lower blanks, and means for operating the gate and friction feeder in timed relationship.
- 15 8. In mechanism of the character described, a hopper for a pile of blanks, and means for simultaneously lifting and feeding out the lower blank of the pile, said means comprising a plurality of rotary disks having friction humps which are adjustable in length.
- 20 9. A blank-feeding mechanism comprising a hopper for a pile of blanks, means for feeding blanks successively from the pile, and means forming an outlet passage-way for a single blank at a time, said passage-way forming means comprising a recessed rotary member and a gate strip cooperating therewith.
- 25 10. A blank-feeding mechanism comprising side guides for a pile of blanks, a friction feeder to act on successive lower blanks of the pile, a rotary member over which each of said lower blanks passes, and a gate member cooperating with said rotary member in forming an outlet for said passing blank, said rotary member having a recess or space to receive and permit the free passage of an attachment to a blank or an extra thick portion thereof.
- 30 11. In a blank-feeding mechanism having a hopper for a pile of blanks and means for feeding blanks successively from the bottom of the pile, a pair of laterally adjustable vertical guide strips for side edges of the blanks, the lower ends of said guide strips 35 being spaced above the bottom of the hop-
- per to permit laterally projecting edge portions of the blanks to pass under the strips.
12. In mechanism of the character described, a support for a pile of blanks, means for intermittently retracting said support, 50 and means independent of said support for raising the pile and advancing the lower blank therefrom.
13. A blank-feeding mechanism including a normal support for a pile of blanks, 55 said support having a stationary super-frictional surface, means providing an outlet for a single blank at a time from the bottom of the pile, and a plurality of rotary friction feeders below said support and located 60 at different distances from said outlet, each of said rotary feeders having a cam-shaped periphery the higher portion of which is adjustable in length, whereby movement of the lower blank through said outlet may 65 be continued by the action of a feeder near the outlet after a portion of the next or second blank rests upon said stationary frictional support.
14. A blank-feeding mechanism including 70 a normal support for a pile of blanks, a friction feeder to act on successive single blanks of the pile, said feeder being constructed and arranged to shift from a plane below the normal support to a plane above 75 it, and means for intermittently retracting the said support.
15. A blank-feeding mechanism including a normal support for a pile of blanks, a rotary recessed member for acting successively 80 on single blanks of the pile, a gate member cooperating with said rotary member in forming an outlet for the blanks, and means for intermittently retracting said support. 85

In testimony whereof we have affixed our signatures.

LEON E. LA BOMBARD.
MELVIN H. SIDEBOTHAM.
